FIG. 1

FIG. 2

FIG. 3

FIG. 4

FIG. 5

FIG. 6

FIG. 7

FIG. 8

FIG. 9

FIG. 1 is a perspective view of a radiator cover embodying my novel design.

FIG. 2 is a front elevational view thereof.

FIG. 3 is a top view of said cover.

FIG. 4 is a sectional view taken along line 4—4 of FIG. 1, but showing the top grill and front wall only.

FIGS. 5 and 6 are top views of modified forms of the radiator cover of my new design.

FIG. 7 is an enlarged fragmentary plan view of the form of the invention shown in FIG. 3.

FIG. 8 is an enlarged fragmentary plan view of the form shown in FIG. 5; and

FIG. 9 is an enlarged fragmentary plan view of the form shown in FIG. 6.

FIGS. 1 through 3 and 5 through 9 are broken away to indicate indeterminate length and a portion of the front wall in FIG. 4 is omitted for convenience of illustration only.

I claim:

The ornamental design for a radiator cover, substantially as shown and described.
